UNITED STATES PATENT OFFICE.

ELLA CONNELL SMITH, OF NEW YORK, N. Y.

DESIGN FOR A DOOR OR COVER.

SPECIFICATION forming part of Design No. 27,021, dated May 4, 1897.

Application filed March 19, 1897. Serial No. 628,352. Term of patent 7 years.

To all whom it may concern:

Be it known that I, ELLA CONNELL SMITH, a citizen of the United States, residing at New York, in the county of New York and State 5 of New York, have invented and produced a new and original Design for Safety Balcony-Doors; and I do declare the following to be a full, clear, and exact description of the same, reference being had to the accompanying drawings, forming a part thereof.

The annexed drawings, to which reference is made, fully illustrate my invention or design, in which—

Figure 1 represents a plan view of my design, Fig. 2 is a vertical longitudinal sectional view of the same, and Fig. 3 is a vertical transverse sectional view of the same, these three figures or views being deemed necessary to fully illustrate my design.

20 The leading feature of my design consists of the raised central portion, at the apex of which is a cap-plate, connecting inclined bars which connect with horizontal and transverse bars, that are plainly shown when viewed as 25 in Fig. 1 of the annexed drawings.

Referring by letter to the accompanying drawings, A designates the design for balcony-doors or doors for openings in floors, the general outline or contour of which presents a frame composed of bars *a a b b*, the former 30 being the longitudinal bars and the latter the end transverse bars. The sides and ends of this cover or door presents inclined surfaces *c c d d* when viewed in longitudinal section as well as transverse section, as shown in 35 Figs. 2 and 3 of the drawings. These inclined surfaces extend from the rectangular frame upwardly and inwardly, terminating at the point *e* of the apex of the door.

What I claim is—

40 The design for doors or covers for openings in floors as herein shown and described.

In testimony whereof I affix my signature in presence of two witnesses.

ELLA CONNELL SMITH.
